D. E. ODOM

OVERWINDING PREVENTER

Filed Dec. 6, 1922

UNITED STATES PATENT OFFICE.

DANIEL E. ODOM, OF BENNETTSVILLE, SOUTH CAROLINA.

OVERWINDING PREVENTER.

Application filed December 6, 1922. Serial No. 605,300.

To all whom it may concern:

Be it known that I, DANIEL E. ODOM, a citizen of the United States, residing at Bennettsville, in the county of Marlboro and State of South Carolina, have invented certain new and useful Improvements in Overwinding Preventers, of which the following is a specification, reference being had to the accompanying drawings.

10 This invention relates to certain improvements in overwinding preventers and it is an object of the invention to provide a novel and improved device of this general character wherein the means for rotating the winding shaft of a spring becomes inoperative when the spring has been wound to a predetermined degree.

It is also an object of the invention to provide a novel and improved device of this 20 general character comprising two members one threaded upon the other, whereby said members are normally maintained for unitary rotation but are disconnected upon abnormal resistance being offered by the spring 25 being wound upon unitary rotation of said members.

An additional object of the invention is to provide a novel and improved device of this general character comprising two members 30 normally connected for unitary rotation together with means for rendering said connection inoperative upon undue resistance being offered to one of the members and whereby the second member will rotate freely independently of the first named member.

Furthermore it is an object of the invention to provide a novel and improved device of this general character comprising two rotatable members having associated therewith means for normally connecting the same for unitary rotation, said means becoming inoperative upon undue resistance being offered to one of the members and in a manner whereby the second member may readily rotate with free handle.

The invention consists in the details of construction and in the combination and arrangement of the several parts of my improved overwinding preventer whereby certain important advantages are attained and the device rendered simpler, less expensive and otherwise more convenient and advantageous for use, as will be hereinafter more 55 fully set forth.

The novel features of my invention will hereinafter be definitely claimed.

In order that my invention may be the better understood, I will now proceed to describe the same with reference to the accompanying drawings, wherein:—

Figure 1 is a fragmentary view partly in section and partly in elevation illustrating an overwinding preventer constructed in accordance with an embodiment of my invention and in applied position;

Figure 2 is a view partly in section and partly in elevation of the preventer as herein disclosed unapplied and with certain of the parts in a second position and wherein the washer is operatively engaged with the head and the nut member 3 therefrom;

Figure 3 is a view similar to Figure 2 with the nut member and washer free of the head to permit the head to rotate with substantially a free handle;

Figure 4 is a sectional view taken substantially on the line 4—4 of Figure 2;

Figure 5 is a sectional view taken substantially on the line 5—5 of Figure 3;

Figure 6 is a sectional view taken through the nut member and washer;

Figure 7 is a view in plan of the washer; and

Figure 8 is a view in plan of the nut member.

As herein disclosed, W denotes a winding shaft for a spring S, the same being comprised in a motor structure or the like, said shaft having a socket 1 in the outer end portion thereof to provide means whereby my improved winding preventer may be operatively engaged therewith. The socket 1 is adapted to have threaded thereto a shank or shaft section 2 secured to and extending outwardly from the axial center of a plate 3. The plate 3 has aligned therewith and spaced therefrom a second plate 4, the plate 4 being tied or connected to the plate 3 through the instrumentality of a plurality of rods 5.

The plate 4 at its axial center is provided with an opening 6 which snugly receives a reduced portion of an elongated cylindrical head 7. The opposite end portion of the head 7 is provided with a socket or recess 8, which receives the inner portion or head 9 of the shank or shaft section 2, hereinbefore referred to, whereby the head 7 is supported for rotation. Extending out-

wardly from the reduced portion 7 is an extension 10 through which a handle or other operating means is adapted to be engaged. The portion of the head 7 adjacent to the plate 3 is provided with the outstanding spiral threads 11 with which is engaged the nut member 12. The periphery of the member 12 is provided with suitably positioned recesses or grooves 14 which receive the adjacent portions of the rods 5 whereby the nut member 12 is held against rotation but is free to have movement lengthwise of the head 7. The threads 15 of the nut member 12 constitute grooves or channels. Loosely surrounding the head 7 inwardly of but immediately adjacent to the nut member 12 is a washer 16 provided at its outer marginal portion with suitably positioned elongated recesses or notches 17 which receive the rods 5, the ends of each of said notches or recesses 17 providing stop shoulders 18 for contact with a rod 5 whereby the washer 16 is permitted to have limited rotation independently of the nut member 12.

Interposed between the plate 4 and the nut 12 is an expandable member 19 herein disclosed as a coiled spring encircling the head 7 and which operates to constantly urge the nut member 12 and the associated washer 16 toward the plate 3 whereby the nut member 12 is normally maintained in threaded engagement with the head 7.

The inner marginal portion of the washer 16 is provided with suitably positioned notches or recesses 20 each one of which is adapted to coincide with an end of a groove or channel 15 when the washer 16 is at the limit of its movement in one direction so that the nut member 12 and the washer 16 may normally have requisite driving connection with the head 7.

With the nut member 12 and washer 16 normally in their locking engagement with the head 7, said head 7 and the shank or shaft section 2 will be caused to rotate in unison to effect the requisite turning movement of the shaft W to wind the spring S associated with said shaft.

When the spring S has been wound to a desired degree the resistance of the spring S will sufficiently retard the rotation of the shaft W to cause the nut member 12 to move against the tension of the expandable member or spring 19 to an extent to disengage the nut member 12 from the threads 11 whereby the head 7 will be caused to rotate independently of the plate 3 and with substantially a free handle. As the nut member 12 passes out of engagement with the threads 11 the pitch of said threads will impart sufficient rotation to the washer 16 to cause the inner marginal portions 20' of said washer immediately adjacent to the notches or recesses 20 therein to close the

inner ends of the grooves or channels 15 whereby the nut member 12 is held against being returned by the expandable member or spring 19 into engagement with the threads 11 of the head 7. The extent of movement of the washer 16 as effected by the rotation of the head 7 is limited by contact of a second stop 18 of each of the recesses or notches 17 with a rod 5. With the washer 16 in this position the head 7 may be freely rotated without causing rotation of the plate 3 and the shaft W with which it is connected.

If it is desired to cause the nut member 12 together with the washer 16 to again have desired engagement with the head 7 it is only necessary to impart a slight reverse rotation to the head 7 until each of the recesses 20 of the washer 16 is brought into registry with its associated groove or channel 15.

It is to be understood that the inner marginal portion 20' of the washer 16 engages within the grooves or channels 15 of the nut member 12 whereby the washer is caused to have movement in unison with the member 12 and also whereby the requisite independent rotation of the washer 16 is effected. I also have interposed between the plates 3 and 4 an enclosing sleeve 21 which serves to protect the housed elements against dust or the like and also provide means whereby lubricant may be held to such elements to facilitate the operation thereof.

From the foregoing description it is thought to be obvious that an overwinding preventer constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a shaft and means placed under tension by the shaft upon rotation thereof, a structure, means for coupling the structure to the shaft, a head rotatably supported by the structure and provided with means for rotating the same, a portion of said head being provided with threads, a nut member engaged with the threads, means comprised in the structure for holding the nut member against rotation but permitting the same to have movement lengthwise of the head, means for constantly urging the nut member toward the threads, and means

for holding the nut member against engagement with the threads of the head.

2. In combination with a shaft and means placed under tension by the shaft upon rotation thereof, a structure, means for coupling the structure to the shaft, a head rotatably supported by the structure and provided with means for rotating the same, a portion of said head being provided with threads, a nut member engaged with the threads, means comprised in the structure for holding the nut member against rotation but permitting the same to have movement lengthwise of the head, means for constantly urging the nut member toward the threads, means for holding the nut member against engagement with the threads of the head, and means movable with the nut member as the same passes free of the threads of the head to hold said member against engagement with said threads.
3. In combination with a shaft and means placed under tension by the shaft upon rotation thereof, a structure, means for coupling the structure to the shaft, a head rotatably supported by the structure and provided with means for rotating the same, a portion of said head being provided with threads, a nut member engaged with the threads, means comprised in the structure for holding the nut member against rotation but permitting the same to have movement lengthwise of the head, means for constantly urging the nut member toward the

threads, and means for holding the nut member against engagement with the threads of the head, a washer surrounding the head and positioned adjacent the inner face of the nut member, said washer being also engageable with the threads of the head member and passing out of engagement therewith together with the nut member upon rotation independent of the head member, said washer when free of the threads having limited rotation in a direction to prevent the nut member reengaging the threads.

4. In combination with a shaft and means placed under tension by the shaft upon rotation thereof, a structure, means for coupling the structure to the shaft, a member rotatably supported by the structure, a second member mounted upon the first named member, coacting means carried by the last named member and the structure for holding said last named member against rotation, coacting means for normally holding both of the members for unitary rotation, said means operating to move the second named member lengthwise of the first named member into a release position upon predetermined resistance being offered to the unitary rotation of the members, and automatic means for imparting movement to the second member in the opposite direction.

In testimony whereof I hereunto affix my signature.

DANIEL E. ODOM
